UNITED STATES PATENT OFFICE.

NAPOLEON DU BRUL, OF CINCINNATI, OHIO.

TREADLE.

SPECIFICATION forming part of Letters Patent No. 645,466, dated March 13, 1900.

Application filed June 24, 1899. Serial No. 721,760. (No model.)

To all whom it may concern:

Be it known that I, NAPOLEON DU BRUL, a citizen of the United States of America, and a resident of Cincinnati, in the county of Hamilton and State of Ohio, have invented certain new and useful Improvements in Treadle Mechanisms, of which the following is a specification.

My invention relates to a removable treadle mechanism and to means whereby the treadle mechanism can be suspended in elevated position away from the floor to enable the washer, scrubber, or sweeper to readily clean the part of the floor beneath the machine-frame and at the same time placing the treadle mechanism in convenient position for the machinist to oil the bearings thereof.

My improved treadle mechanism comprises a pair of similarly-constructed right and left uprights or standards adapted to occupy a position between the end frames of a machine and an upper brace-rod of the end frames and the floor on which the machine is set up and a treadle-plate supported by a brace or tie rod between the uprights or standards, each upright or standard being constructed with a recessed upper end, providing lips or fingers adapted to receive and engage the upper brace-rod and to enable the uprights or standards to act as stays for the machine when in their normal position between the central brace-rod and the floor and provided with a hook at its middle part, whereby the treadle mechanism is suspended from the central brace-rod when detached and lifted up from the floor, as hereinafter described and claimed.

In order that my invention may be fully understood, I will proceed to describe it with reference to the accompanying drawings, in which—

Figure I is a front elevation of my improved treadle mechanism, showing it in connection with a part of a machine-frame and in normal position. Fig. II is an end elevation of the same. Fig. III is a vertical central section taken on the line III III, Fig. I, showing the treadle mechanism elevated.

The drawings show the lower parts of two end frames 1 of a machine, having feet 2 secured to a floor by bolts 3.

4 are lower brace or tie rods having screw-threaded reduced ends extending through the end frames and secured by nuts 5. 6 is an upper central brace or tie rod, also having screw-threaded reduced ends extending through the end frames and secured by nuts 7.

Between the end frames and beneath the upper brace-rod is located my improved treadle mechanism.

8 shows a pair of right and left uprights or standards similarly constructed, each formed with a base or foot piece 9, having inwardly-projecting lugs or stops 10, with a transverse recess 11 and lips or fingers 12 at its upper end and with a recess 13 and hook 14 at the middle portion of the upright or standard.

15 is a brace or tie rod having screw-threaded reduced ends extending through the uprights and secured by nuts 16. This brace-rod 15 supports a treadle-plate 17, formed with pendent perforated ears 18, through which the brace-rod 15 extends.

19 is a socket formed on the rear part of the treadle-plate to receive the lower end of the operating-rod 20, which is hinged by a pintle 21 within the socket. The pintle 21 is secured by nuts 22.

The uprights of the treadle mechanism being formed with recesses in their upper ends enables them to be placed in a position between the end frames and beneath the upper brace-rod to fit against the latter and provide stays between the upper brace-rod and the floor, whereby the treadle mechanism is rigidly held and the machine-frame is strengthened, while the treadle mechanism can be readily withdrawn when it is desired to suspend it from the upper brace-rod.

To remove the treadle mechanism and raise it, the upper parts of the uprights are grasped with the two hands and pulled from under the upper brace-rod and the device is lifted up and hung by the hooks on the upper brace-rod, where it is suspended or hangs pendent out of the way of the washer, scrubber, or sweeper. When desired, the treadle mechanism can be lifted off the upper brace-rod in the same manner and replaced in normal position.

It will be observed that none of the parts of the treadle mechanism are disarranged by the temporary elevation thereof.

Having thus described my invention, the following is what I claim as new therein and desire to secure by Letters Patent:

1. A treadle mechanism comprising a pair of detachable uprights providing stays each having lips at their upper ends extending in line therewith and adapted to engage an upper brace-rod of a machine-frame, and wedge thereunder and a treadle-plate pivoted to the lower parts of the uprights; substantially as described.
2. A treadle mechanism comprising a pair of uprights, means for detachably connecting them to a machine-frame, a downwardly-pro-

jecting hook near the middle part of each upright, whereby the treadle mechanism may be supported on an upper brace-rod of the machine-frame in an elevated position; substantially as described.

3. A treadle mechanism comprising a pair of uprights, each having lips at their upper ends, and a downwardly-projecting hook near its middle part; substantially as described.

NAPOLEON DU BRUL.
